2,420,230

PHASE MODULATION RECEIVER

Murray G. Crosby, Riverhead, N. Y., assignor to
Radio Corporation of America, a corporation
of Delaware

Original application October 25, 1941, Serial No.
416,443. Divided and this application October
31, 1944, Serial No. 561,289

8 Claims. (Cl. 250—27)

1

My present invention relates generally to angular velocity-modulated carrier wave receivers, and is a division of my application Serial No. 416,443, filed October 25, 1941, Patent No. 2,363,-649, dated November 28, 1944.

Undesired amplitude modulation effects existing on an angular velocity-modulated carrier wave have been removed in the past by means of a limiter, a balanced detector or by a combination of both devices. By "angular velocity-modulated carrier wave" is meant a phase or frequency modulated carrier wave. The expression "time-modulated" may, also, be used hereinafter generically to designate such types of modulation.

The limiter is effective in removing amplitude modulation at all times even in the presence of frequency modulation, but the balanced detector is only completely balanced for the condition when no frequency modulation is present on the received carrier wave. Hence, when the balanced detector is depended upon to remove the undesired amplitude modulation the elimination is only complete in the absence of the desired modulation, and becomes progressively poorer as the desired modulation is increased.

Basically, my present invention involves the utilization of detected amplitude modulation existing on the angular velocity-modulated carrier wave to modulate the detected modulated carrier wave energy such phase that the undesired amplitude modulation is greatly reduced. Hence, if desired, the limiter may be dispensed with, since the elimination of the amplitude modulation by the balanced detector is made more complete. By omitting the limiter the gain of the receiver may be decreased, since the large signal voltages required to saturate the limiter do not have to be provided. Economy of construction and simplification follow as a result of gain reduction prior to the demodulator.

Other features of my invention will best be understood by reference to the following description taken in connection with the drawing in which I have indicated diagrammatically several circuit organizations whereby my invention may be carried into effect.

Fig. 1A shows the wave form of the detected output of a frequency modulated carrier wave (FM);

Fig. 1B illustrates the same wave form when using the present invention; and

Figs. 2 and 3 show respectively different embodiments of the invention, it being noted that

2

present Fig. 3 corresponds to Fig. 6 of my aforesaid patent.

Referring to the accompanying drawings, wherein like reference characters in the different figures designate similar circuit elements, there will first be considered the manner in which the present inverse modulation method effects substantial suppression of the amplitude modulation (AM) existing on the carrier. Fig. 1A shows the manner in which the presence of amplitude modulation is manifested in the frequency modulation receiver demodulator output. Wave A is the desired detected frequency modulation output which is assumed (in order to clarify the explanation) to have a higher frequency than the undesired amplitude modulation frequency. The undesired amplitude modulation appears as an amplitude envelope as shown by wave B of Fig. 1A. The undesired amplitude modulation is assumed to produce a 25 percent modulation of the incoming signal.

In the receiver of this invention, an amplitude modulation output is provided having the wave form of the amplitude envelope B. This output is used to modulate the amplitude of wave A in a sense which causes a reduction of amplitude when the wave is at point a on the envelope, and an increase in amplitude when the wave is at point b. The inverse modulation thus applied, therefore, opposes the undesired amplitude modulation which is present, and tends to cancel it. Fig. 1B shows the result of applying the inverse amplitude modulation to the FM wave of Fig. 1A. The resulting AM envelope B' is of double frequency and greatly reduced amplitude.

In Fig. 2 there is shown only so much of an FM receiver as is essential to a proper understanding of the invention. Let it be assumed that the balanced detectors 2—3 are preceded by the usual pre-demodulator stages of a superheterodyne receiver adapted to operate in the ultra-high frequency band, say 42 to 50 megacycles (mc.), in which FM reception is had. As is well known, the FM wave is produced by deviating the carrier frequency in accordance with the modulation amplitude, the rate of deviation being a function of the modulation frequencies per se.

A phase modulated wave (PM) may be considered as an FM wave which has been modulated with an input proportional to the modulating frequency. At present, a maximum center frequency (F_c) deviation of 75 kilocycles (kc.) is used for FM broadcasting. In the superheterodyne receiver the FM waves are reduced to an

intermediate frequency (I. F.), although the same frequency deviation range is retained. The FM waves, with center frequency of the I. F. value, are to be understood as applied to the resonant primary circuit 1 tuned to the I. F. value. This invention is applicable to FM waves having a high or low frequency deviation ratio.

Diodes 2 and 3 are coupled to the input circuit 1 by a network which has been disclosed in my U. S. Patent No. 2,296,092, granted September 15, 1942. Such a detection network provides balanced detected FM voltage and a separate AM voltage. The anode of diode 2 is connected to its cathode through a series path comprising secondary circuit 1', resistor R₁ and resistor R₂, the two resistors being shunted by the bypass condenser C₁. The anode of diode 3 is connected to its cathode through a series path comprising the secondary circuit 1'', resistor R₃ and resistor R₄, the bypass condenser C₂ shunting resistors R₃—R₄.

Each of circuits 1' and 1'' is magnetically coupled to tuned circuit 1, but circuits 1' and 1'' are equally and oppositely mistuned relative to the I. F. value of circuit 1 by any predetermined frequency value. As explained in my aforesaid Patent No. 2,296,092 detected FM voltage is developed across resistors R₂ and R₄ which are arranged in polarity opposition, it being noted that the cathode end of resistor R₄ is at ground potential.

The detected AM voltage may be taken off at the anode end of resistor R₁. This type of discriminator converts applied FM waves to AM waves with modulation envelopes 180 degrees out of phase. These modulation envelopes are detected by diodes 2 and 3 which make the detected outputs available across resistors R₁—R₂ and resistors R₃—R₄. The manner in which resistors R₁—R₂ and resistors R₃—R₄ are connected together makes the detected FM voltage available across resistors R₂—R₄. The detected AM voltage is taken from across resistors R₁ and R₄. It will be noted that these two resistors R₁ and R₄ are connected so that they both have their anode ends at negative potential, and the combination of the detected AM voltage outputs is in phase. The normal adjustments of the resistors are to make them all equal in order to effect balanced conditions for both AM and FM reception. Bypass condensers will bypass the I. F. currents fed to the discriminator, but allow the modulation frequencies to pass. There will, then, be derived from the upper end of resistor R₂ the detected FM voltage which, also, has superposed thereon the detected AM effects which are to be eliminated.

The cathode end of resistor R₂ is connected to ground through a series path comprising condenser C₃ and resistor 6. An adjustable tap 6' is provided to take off from the resistor 6 any desired magnitude of voltage thereacross. In the same way the series path comprising condenser C₄ and resistor 5 acts as a potentiometer connected between the anode end of resistor R₁ and ground. The tap 5' slidable along resistor 5 provides an adjustment for feeding a desired magnitude of detected AM voltage to tube 4. The latter acts as an inverse modulator tube.

Tube 4 shows a pentagrid tube including a cathode 11, a plate 12 and five successive grids 4', 4'', 13, 14 and 15. The second input grid 4'' is connected by tap 6' to the resistor 6, and has the detected FM voltage applied thereto. The first input grid 4' is connected by tap 5' to

resistor 5, and has the detected AM voltage impressed thereon. The plate 12 of tube 4 is connected to a source of positive voltage through load resistor 10, the screen grids 13 and 14 on either side of grid 4'' being connected to the same source through a voltage reducing resistor 10'. The grid 15 is a suppressor and is at cathode potential.

In a modulator of the type shown at tube 4 the carrier is usually fed to the third grid 4'', and appears across a tuned circuit in the plate circuit. The modulation applied to the first grid is normally of a frequency such that the tuned circuit does not pass it. However, in this type of audio modulator a resistor 10 is employed in the plate circuit, and there appears across the resistor in amplified form the detected AM voltage originally applied to grid 4'. There, also, appears across the resistor 10 the inversely modulated detected FM voltage.

In other words, at tube 4 the detected AM voltage is applied to grid 4' in such a phase relation to the detected FM voltage at grid 4'' that the wave form of the resultant inversely modulated detected FM voltage is as shown in Fig. 1B. The inverse modulation causes a rise in the gain of modulator tube 4 when the undesired AM causes a reduction of the incoming signal amplitude, and a decrease in gain when the signal amplitude is modulated upward.

The amplified AM voltage appearing as such across resistor 10 may be removed from the modulator output by means of a balancing system embodying tube 7. The latter, for example, 35 may be a twin triode tube. The common cathode connection of tube 7 is connected through a resistor 8' to the grounded end of potentiometer resistor 8. The upper end of the latter is connected to the plate end of resistor 10 by a condenser C₅. The grid 7' of one of the triodes of tube 7 is connected by an adjustable tap along resistor 8, while the grid 7'' of the other triode is connected by lead 10'' to the adjustable tap 5' which feeds the detected AM voltage to grid 4'. The plates of tube 7 are connected in parallel to a common source of positive direct current voltage through load resistor 9.

As the detected AM voltage is amplified by the modulator tube 4 its phase is reversed. When 50 combined in-phase, as is done by tube 7, bucking results. Potentiometer 8 may be adjusted so that the undesired detected AM voltage transmitted through the modulator just cancels that fed to the grid 7'' of tube 7. The output voltage 55 appearing across resistor 9 is, then, the pure modulated output which consists of an inverse amplitude modulation applied to the detected FM wave form. That is, the output appearing across resistor 9 has the wave form A'-B' of Fig. 1B.

At first it might be assumed that the undesired amplitude modulation may be completely cancelled by this present modulation process. However, that this is not possible will be realized when the condition of 100% amplitude modulation is considered. It is obvious that when the amplitude modulation modulates the carrier to zero amplitude, it would take an infinite amount of gain to bring it back to normal amplitude.

On the other hand, for the upward peaks of amplitude modulation the condition of 100% upward modulation may be compensated for by a reduction in gain of 2:1. Thus, the upward and 75 downward swings of the modulation do not follow

a linear law which allows complete cancellation by a simple application of reverse modulation. The degree of reduction possible by this reverse modulation process has been evaluated in my aforesaid Patent No. 2,363,649, and need not be repeated here.

The method employed in the present invention may be applied to the reception of phase modulated carrier waves (PM). The claims of this divisional application are directed to such method and the apparatus employed therein. In phase modulation reception the presence of amplitude modulation produces the same kind of modulation of the output as in the case of FM waves. Consequently, the same type of circuits may be used for reducing the undesired component. Referring to Fig. 3, which shows a receiving system for PM waves, the tube 48 is an I. F. amplifier on which are impressed PM waves whose center frequency has been reduced to the I. F. value. The I. F. transformer 41, whose primary and secondary circuits are each fixedly resonated to the operating I. F. value, is adjusted to be of the band pass type.

The coil of the tuned secondary circuit is mid-tapped to ground for the purpose of providing neutralizing voltage for the piezo-electric crystal 42. The crystal is included in a crystal filter network, and provides a phase modulation discriminator of the over- and under-neutralized type as described in my U. S. Patent 2,204,575. It is not believed necessary to describe the crystal filter network, since my latter patent has a full and complete description thereof. The neutralizing condensers 70, 71 are adjusted so that an over-neutralized characteristic is presented to one of the two diodes 43 and 44, while an under-neutralized characteristic is provided with respect to the other of the diodes. This produces a balanced phase modulation detector which delivers AFC (automatic frequency control) voltage at the terminal designated AFC. Detected PM voltage is developed across the potentiometer resistor 49. It will be understood that the specific PM demodulator shown is but an illustration of one of many types of PM demodulators which may be used.

Tube 47 is a separate multi-grid detector for amplitude modulation detection. For this detection, filtered carrier is obtained by combining the over- and under-neutralized outputs of the crystal filter by means of condensers 80 and 81. This combination produces a neutralized filter output which is fed to the input grid 84 of limiter tube 48. The construction of the latter type of limiter is disclosed in my U. S. Patent No. 2,276,565, granted March 18, 1942. The output of the limiter tube is fed through condenser 92 to the first input grid 82 of detector tube 47, while the second input grid 83 is fed through condenser 90 with the unfiltered PM signal energy from the secondary of transformer 41. This combination of filtered carrier and unfiltered PM signal energy is adjusted for amplitude modulation detection by means of phase shifters 90-91 or 92-93. Reference is made to my aforesaid U. S. Patent 2,276,565 for a more complete description of the operation of limited tube 48. The limiter functions to hold the filtered carrier fed to grid 84 substantially constant to avoid distortion to selective fading. By using a limiter ahead of the AM detector 47 a more linear characteristic results because the detector output is proportional to the product of the carrier amplitude and unfiltered PM signal energy.

The proper phase relation for amplitude modulation detection at detector 47 is either zero or 180 degrees. The type of AM detector shown is that disclosed in my U. S. Patent No. 2,063,588 granted December 8, 1936. Reference is made thereto for a full disclosure of the relations existing between the voltages on grids 82 and 83 to detect AM waves. The detected AM voltages per se may be taken from across the output load 10 circuit 85 of detector tube 47 by leads 86. The detected AM voltage is, also, fed to the third grid 89 of modulator tube 45 so that its amplitude modulates the detected PM voltage which is fed to the first grid 94 by potentiometer 49. The potentiometer 87 across resistor 85 provides over lead 88 the AM voltage for grid 89. The tube 45 functions as the inverse modulator tube in this circuit. The modulation process occurring at tube 45 is adjusted to have the right phase to oppose the undesired AM envelope which exists on the detected PM voltage envelope at potentiometer 49. The phase may be adjusted by reversing the phase of either the filtered carrier or unfiltered signals fed to the grids of AM detector tube 47. The tube 7 operates, as disclosed in Fig. 2, to balance out the amplification of the detected AM component in the output circuit of the inverse modulator tube 45.

Tube 7, a twin triode, functions to balance out the amplified AM component developed during the inverse modulation process by virtue of the inherent amplifying property of tube 45. Since the detected AM voltage fed over lead 88 is applied to grid 89 of tube 45, there will be developed across plate resistor 100 the said AM voltage in amplified form. Hence, even though the inverse modulation step tends to minimize the undesired AM envelope of the detected PM voltage, yet the amplification property of tube 45 introduces an amplified AM component in the modulator tube output. The plate side of resistor 100 is connected through lead 101 and potentiometer 102 to control grid 103 of the upper triode section of tube 7. The control grid 104 of the lower triode section is connected to the potentiometer 87. The plates 105 and 106 of the two triodes are connected in parallel to the upper end of output resistor 107. The output leads 108 supply the PM voltage component, substantially free of the undesired AM component since the AM voltages on grids 103 and 104 act to balance out in the common plate circuit of tube 7.

While I have indicated and described one system for carrying my invention into effect, it will be apparent to one skilled in the art that my invention is by no means limited to the particular circuits shown and described, but that many modifications may be made without departing from the scope of my invention.

60 What I claim is:

1. A method of receiving phase modulated carrier waves which have undesired amplitude modulation thereon, which includes deriving a first modulation voltage from the waves corresponding to the phase modulation and undesired amplitude modulation, deriving from the phase modulated carrier waves filtered carrier energy, combining said filtered energy and unfiltered phase modulated carrier waves in such phases as to provide a second modulation voltage corresponding to said undesired amplitude modulation, and subjecting both said modulation voltages to a modulation step in such relative phases that said undesired amplitude modulation of said 65 first modulation voltage is substantially reduced.

2. In a method as defined in claim 1, substantially compensating the amplification effect of said modulation step on said second modulation voltage by combining said second modulation voltage with the product of said modulation step in opposed relation.

3. A method of deriving the desired modulation from phase modulated carrier waves which is provided with undesired amplitude modulation, including deriving from said waves a modulation voltage representative of the phase modulation and undesired amplitude modulation, deriving from said waves a second modulation voltage representative of said undesired amplitude modulation, and inversely modulating the first modulation voltage with the second modulation voltage thereby to reduce said undesired amplitude modulation.

4. In a method as defined in claim 3, balancing out said second modulation voltage, produced in amplified form during said inverse modulation, by combining in balancing relation said second modulation voltage with the product of said inverse modulation.

5. In a method as defined in claim 1, the step of limiting said filtered carrier energy prior to said combining step.

6. In a method as defined in claim 1, said modulation step involving an undesired amplification of said second modulation voltage, and treating the product of said modulation step with the amplified modulation voltage to eliminate the latter.

7. In a system for receiving phase modulated carrier waves, means for detecting the waves to provide a first modulation signal representative of the phase modulation, means for detecting the waves to provide a second modulation signal representative of undesired amplitude modulation of the carrier waves, means for inversely modulating the first modulation signal with the second modulation signal, and additional means for balancing out said second modulation signal amplified during said inverse modulation.

8. A method of receiving carrier waves whose modulation includes both phase and amplitude components, separately detecting the waves to provide a modulation signal having both components, and a second modulation signal having essentially said amplitude component, and combining the two modulation signals in an inverse modulation step to reduce to a substantial extent said amplitude component.

MURRAY G. CROSBY.
